UNITED STATES PATENT OFFICE

MILFORD T. VANDERVOORT, OF GRAND RAPIDS, MICHIGAN, ASSIGNOR TO AMERICAN SEATING COMPANY, OF GRAND RAPIDS, MICHIGAN, A CORPORATION OF NEW JERSEY

UPHOLSTERING MACHINE

Application filed April 29, 1929. Serial No. 358,908.

The present invention relates to upholstering machines; and its object is to provide an improved machine of that character whereby the base member of a cushion seat may be held in exactly predetermined position while the cover sheet is being applied thereto; and further, to provide such a machine whereby the springs of such a seat may be held against excess compression while said cover sheet is being thus applied; and further, to provide such a machine whereby said base member may be securely held while the tacks or attaching means for such cover sheet are driven thereinto; and further and more generally, to provide such a machine which may be very efficiently and readily operated.

This object is attained by, and the invention finds preferable embodiment in, the machine hereinafter particularly described in the body of this specification and illustrated by the accompanying drawings, in which:

Figure 1 is an elevational side view of an upholstering machine with a cushion seat in position thereon, certain parts being shown in medial vertical section;

Figure 2 is a fragmentary view of the same showing the parts in their position prior to the lowering of said base member and parts carried thereby upon the cover sheet of the cushion seat;

Figure 3 is a horizontal sectional view of the machine taken on line 3—3 of Figure 1, the turntable of the machine being omitted; and

Figure 4 is a vertical sectional view of certain parts of the machine taken on line 4—4 of Figure 3.

In the embodiment of the invention illustrated by these drawings, my upholstering machine has a suitable supporting framework 1 formed of angle iron or the like and has suitable raising and lowering mechanism, as the axially vertical cylinder 2 containing a piston 3, its plunger rod 4 having a flat head 5. This cylinder, as indicated, is supplied with compressed air admitted at either end for vertically moving the head 5 up or down. The lower cylinder head carries a vertical sleeve 6 surrounding the plunger rod 4 and provided adjacent its lower end with a radial

flange 7. A collar 8 surrounds and is slidable along this sleeve above flange 7 being urged upwardly by a coiled expansion spring 10 pressing between said flange and collar. The collar 8 has radial extensions 9 on which are pivotally mounted at 11 the arms 12 having lower hook ends 13.

The machine has a base 14 carrying a turntable 15 revolvable about the vertical axis 16 and has a top face 17 which is inclined (as shown) for use in connection with a cushion seat vertically wider at one side edge than at its opposite side edge, as is the seat cushion 18 shown in Figure 1.

In operating this machine the cover sheet 19 used in making the cushion seat is laid on the top face 17 of the turntable, and the head 5 of the piston's plunger rod 4 being raised by admitting air into the lower end of the cylinder 2, the rigid base member 20 of the cushion seat is sustained in the elevated and inverted position seen in Figure 2 by inserting the lower ends of the arms 12 through suitable holes 21 in said base member, whereupon the springs 22 urging these arms toward each other cause the arms' lower hook ends 13 to engage the inner side of said base member adjacent said holes. To prevent the springs 23 pressing between the cushion seat's base member 20 and its wire frame 24 at the top side of the finished cushion seat—and particularly to prevent (as shown) such springs 23 as are adjacent the thicker front edge of the cushion seat from being unduly compressed—bars or struts 25 are passed through holes 26 in the base member 20, having notched lower ends 27 straddling and resting on a wire of said wire frame 24 and having shoulders 28 engaging the under side of said base member (in its inverted position seen in Figures 1 and 2). Air being now admitted into the upper end of cylinder 2, the flat head 5 moves down carrying the collar 8, arms 12 and base member 20 with it and tensioning the spring 10, until the padding 29 carried by said wire frame 24 is pressed on the cover sheet 19 lying on the turntable's top face 17.

This cover sheet is now drawn tautly upward around said padding and over the edges of the base member 20 whereupon it is secured

to its upper side (in the inverted position seen in Figure 1) as by tacks 30. The turntable 15 may be turned about its axis 16, and the collar 8 and parts carried thereby turned 5 with it, to positions convenient for the operative.

It will be seen that a battery of such machines may be arranged side by side in convenient position for the operatives.

10 The invention being intended to be pointed out in the claims, is not to be limited to or by details of construction of the particular embodiment thereof illustrated by the drawings or hereinbefore described.

15 I claim:

1. In a machine for making upholstered seats: a table having a top face adapted to support the flexible cover sheet for the seat; a vertically movable carrier above the base 20 having members adapted to detachably engage the inverted base member of the seat and hold the same in elevated position above the base while said sheet adjacent its edges is being secured to the base member.

25 2. In a machine for making upholstered seats: a table having a top face adapted to support the flexible cover sheet for the seat; a vertically movable carrier above the base having members revoluble horizontally and 30 adapted to detachably engage the inverted base member of the seat and hold the same in elevated position above the base while said sheet adjacent its edges is being secured to the base member.

35 3. In a machine for making upholstered seats: a horizontally revoluble table having a top face adapted to support the flexible cover sheet for the seat; a vertically movable carrier above the base having members revoluble 40 horizontally and adapted to detachably engage the inverted base member of the seat and hold the same in elevated position above the base while said sheet adjacent its edges is being secured to the base member.

45 4. In a machine for making upholstered seats having a base member and a top member with springs therebetween: a table having a top face adapted to support a flexible cover sheet for the seat; a vertically movable carrier rod above the base having a flat head at 50 its lower end; a collar carried slidably on the rod and having members adapted to detachably engage the inverted base member of the seat and hold the same in an elevated position 55 in contact with the head while said sheet adjacent its edges is being secured to the base member.

5. In a machine for making upholstered seats having a base member and a top member with springs therebetween: a table having a top face adapted to support a flexible cover sheet for the seat; a vertically movable carrier rod above the base having a flat head at its lower end; a collar slidable on the rod 60 and yieldingly supported thereby and having

members adapted to detachably engage the inverted base member of the seat and hold the same in an elevated position in contact with the head while said sheet adjacent its edges is being secured to the base member.

6. In a machine for making upholstered seats having a base member and a top member with springs therebetween: a table having a top face adapted to support a flexible cover sheet for the seat; a vertically movable carrier rod above the base having a flat head at its lower end; a collar carried slidably and turnably on the rod and having members 75 adapted to detachably engage the inverted base member of the seat and hold the same in an elevated position in contact with the head while said sheet adjacent its edges is being secured to the base member.

7. In a machine for making upholstered seats having a base member with holes there-through, a top member and springs between said members: a table having a top face adapted to support a flexible cover sheet for the seat; a vertically movable carrier rod above the base having a flat head at its lower end; a collar yieldingly upheld on the rod, turnable therearound, and carrying swingable arms having hook ends adapted to be thrust through the holes and into engagement with the inner side of the inverted base member of the seat and hold the same in an elevated position in contact with said head while said sheet adjacent its edges is being secured to the base member.

8. In a machine for making upholstered seats having a base member with holes there-through, a top member and springs between said members: a table having a top face adapted to support a flexible cover sheet for the seat; a vertically movable carrier rod above the base having a flat head at its lower end; a collar yieldingly upheld on the rod, turnable therearound, and carrying spring-pressed swingable arms having hook ends adapted to be thrust through the holes and into engagement with the inner side of the inverted base member of the seat and hold the same in an elevated position in contact with said head while said sheet adjacent its edges is being secured to the base member.

9. In a machine for making upholstered seats having a base member with holes there-through, a top member and springs between said members: a table having a top face adapted to support a flexible cover sheet for the seat; a vertically movable carrier rod above the base having a flat head at its lower end; a collar yieldingly upheld on the rod, turnable thereround, and carrying swingable arms having hook ends adapted to be thrust through the holes and into engagement with the inner side of the inverted base member of the seat and hold the same in an elevated position in contact with said head while said sheet adjacent its edges is being secured to the base member.

base member; struts adapted to be thrust through holes in said base member and into engagement with the inner sides of said base member and said top member to hold these members of the seat in spaced-apart relation.

In testimony whereof I have hereunto set my hand at Grand Rapids, Michigan, this 25th day of April, 1929.

10 MILFORD T. VANDERVOORT.
